UNITED STATES PATENT OFFICE.

CLAIR H. LONSDALE, OF FORT SAM HOUSTON, TEXAS.

COLLAR BUTTON.

Application filed July 12, 1922. Serial No. 574,403.

To all whom it may concern:

Be it known that I, CLAIR H. LONSDALE, a citizen of the United States, residing at Fort Sam Houston, in the county of Bexar and State of Texas, have invented certain new and useful Improvements in Collar Buttons, of which the following is a specification.

This invention relates to improvements in collar buttons and has as its primary object to provide a button which will facilitate the application of the collar to the neck band of the shirt and the drawing of the tie through the collar. Heretofore it has been customary to provide neck ties with a strip of some smooth finished cloth along the inner sides of their intermediate portions to adapt the ties to slip freely through the collar folds in applying the tie, or means has been provided in connection with the collar for this purpose. The present invention, however, has as its primary object to provide a collar button embodying means adapting the tie to slip freely past the same and which button will furthermore, as stated, facilitate the application of the collar to the neck band of the shirt.

In the accompanying drawing:

Figure 1 is a perspective view illustrating the application of the invention:

Fig. 2 is a detail sectional view through the collar button, collar, and the neck band of the shirt and substantially on the line 2-2 of Fig. 1;

Fig. 3 is a perspective view of the stud member of the button;

Fig. 4 is a perspective view of the socket member of the button;

Fig. 5 is a detail sectional view through the button, the members thereof being assembled.

The button embodying the invention comprises a socket member indicated in general by the numeral 1 and a stud member indicated in general by the numeral 2. The socket member embodies a head 3 and a shank 4 in which is provided the socket 5 and the wall of which shank at its outer side and outer end is formed with an outstanding bead 6 spaced from the head 3. The head 3 and bead 6 adapt the socket member to be assembled with the neck band of the shirt by inserting the beaded end 55 of the shank 4 through the buttonhole at

the back of the neck band in the same manner that an ordinary collar button is applied.

The stud member 2 comprises a head 7 from the rear side of which projects a shank 8 terminating in a snap head 9 which is adapted to be fitted into the socket 5 in the member 1 and retained therein. The said rear side of the head 7 is preferably concave, as indicated by the numeral 10 so that when the head 9 and shank 8 of the stud member have been fitted through the rear buttonhole of a collar and the head 9 is fitted into the socket 5, the marginal portion of the head 7 will be caused to engage firmly against the inner side of the inner fold of the collar due to the collar being gripped between the said head 7 and the beaded end of the socket member 1. The outer or forward side of the head 7 is smooth and free from obstructions and the same is preferably rounded at its margin so that a neck tie may readily slide over the said face of the head. In order that the tie may be supported in such a manner that it will not work down upon the collar and be exposed at the rear thereof, the head 7 is formed at its lower portion with a rearwardly deflected lip 11 over which the lower edge of the tie will engage when the tie is properly arranged between the collar folds.

It will be evident from the foregoing that there is provided a button which will permit of free sliding of the neck tie between the collar folds without any likelihood of binding, and that the button will properly support the tie and will likewise facilitate application of the collar to the shirt and its removal therefrom.

Having thus described the invention, what is claimed as new is:

A collar button including a shank and a head extending radially in all directions from the outer end of the shank, the outwardly presented face of the head being smooth and free from obstructions and relatively flat and the inwardly presented face of the head being concave, the head being provided at its lower end with a tie-supporting lip gradually curved outwardly from the plane of the outer face of the head.

In testimony whereof I affix my signature.

CLAIR H. LONSDALE. [L. s.]
